UNITED STATES PATENT OFFICE.

HENRY E. WARREN, OF ASHLAND, MASSACHUSETTS.

ELECTRIC APPARATUS FOR DRIVING CLOCK OR SIMILAR MECHANISMS.

No. 927,907.

Specification of Letters Patent. Patented July 13, 1909.

Application filed October 22, 1908. Serial No. 458,954.

To all whom it may concern:

Be it known that I, HENRY E. WARREN, a citizen of the United States of America, and a resident of Ashland, in the county of Middlesex and Commonwealth of Massachusetts, have invented Improvements in Electric Apparatus for Driving Clock or Similar Mechanism, of which the following is a specification.

- 10 The invention relates to electrical apparatus for propelling clock or similar mechanism with a minimum expenditure of electrical energy, and consists in the employment, with the usual pendulum or oscillating balance wheel and electro-magnet or other device, by which the pendulum is given periodic impulses to impart energy thereto and keep its arc of oscillation practically constant, of a pair of electric contacts in the circuit with such impulse device, one or both of which contacts are of substantial mass and of resilient material supported in such manner and acted upon by a force such as gravity or the stress of a spring, that they tend constantly to approach each other and normally to remain together, but when separated and allowed to suddenly strike together, will rebound again and again until the resilient or elastic energy due to the diminishing force of impact is dissipated, and the two masses come to rest in close contact. These two masses serve as a make-and-break device in the electric circuit, and one may be stationary and serve as an abutment for the other, 35 which is adapted to move to and from such abutment; or each may be capable of vibratory movement in relation to the other, and one or both may be of resilient material. Means are also provided by which the oscillating pendulum will suddenly separate these contacts near the end of the path of its vibration, preferably in one direction only, although in some instances it may be found desirable to locate a pair of such contacts at 40 each end of such path. Also, an electrical device which has considerable self-inductance in its circuit is preferably employed, to impart impulse to the oscillating pendulum, so that during the vibration or rebounding 45 of the two electric contacts no appreciable current will flow through the circuit and no material impulse will be given to the pendulum, until such contacts come together in a state of rest.
- 50 In the drawings forming a part of this specification, Figure 1 is a front elevation of one

form of the improved electrical devices, and a detached portion of a clock mechanism; Fig. 2 is an elevation of another form of such devices; Fig. 3 is still another form of such devices applied to an oscillating balance-wheel instead of a pendulum; and Fig. 4 is a similar construction to that shown in Fig. 2 with the resilient contacts and magnet coil duplicated.

65 Designating the parts of the apparatus by reference letters, P is the pendulum rod and B the bob, the lower end of which is of magnetic material and swings in close proximity to the pole A of an electro-magnet M.

70 Referring to Fig. 1, the make-and-break electric contacts consist of a lever with small masses C, C', at the respective ends, and supported on a pivot at D, secured in a metal block D'. The center of gravity of this lever 75 is shifted to one side of the pivot by means of a projecting piece E, which gives the mass C a constant tendency to swing toward the other electrical contact or abutment F, which is illustrated as supported upon a flexible 80 strip of metal G secured to metal block H. The two blocks D', H, are connected in circuit with a battery I and the magnet M, by wires W. From the lower mass C' a pin K projects into the path of movement of the 85 pendulum rod P, and near the upper end of the rod P, a pawl L is attached, and extends outward so as to engage the ratchet wheel R of the clock train T. For the purpose of regulating the time of swing of the pendulum, a 90 weight S is mounted upon a screw-threaded portion of the rod P.

Instead of the make-and-break device shown in Fig. 1, the mass C may be mounted upon a flexible strip N, (see Fig. 2), which is 95 held in a metal block N', and a projecting piece p' is attached to the pendulum rod P to strike a pin K for the purpose of separating the contacts C, F, and setting one of them into vibration.

100 In order to limit the time when it is possible to close the electric circuit to a definite portion of the swing of the oscillating device, for the purpose of economizing electric energy, and as a safeguard to prevent the battery from being exhausted when the pendulum is at rest, an auxiliary contact O is provided which is mounted upon a flexible strip Q, supported in the block N' in such a position that when the pendulum rod P hangs 105 perpendicularly, or is swinging through a small sector upon either side of the perpen-

dicular line, it will not touch the contact O. In this arrangement one of the circuit wires W is connected with the pendulum support U instead of with the block N', and the circuit is then through the pendulum rod P, contact O, and strips Q and N, through block N' to the contact C, when the pendulum swings to the left.

In Fig. 3 is illustrated an oscillating balance wheel V supported on a pivot v' which may be employed in place of a pendulum. Upon one side of the rim of the wheel V is a scroll-shaped projection X, upon which the magnet M acts when the circuit W, W, is closed at C, F, and thus gives additional impulse to the oscillation of the wheel V whenever the amplitude of such oscillation decreases so as to fall below the predetermined normal. The rotation of the wheel V is against the stress of the helical spring Y, the inner end of which is secured to the hub of the wheel V and the outer end to a pin y' held in a fixed part of the frame. Upon the periphery of the wheel V is a projecting piece Z, and the strip N is located in such a position in relation to the wheel V that when the arc through which it oscillates is normal, the projection Z will strike the upper end of the strip N and separate the contacts C, F, and set them into vibration, thus breaking the circuit W, W, and causing the magnetic pull of the magnet upon the wheel V to cease or become negligible. As soon, however, as the amplitude of the oscillation diminishes to such a degree that the projection Z does not displace the end of the strip N sufficiently to keep it in vibration during a complete oscillation of the balance-wheel, the contacts C, F, will come together in a state of rest, the circuit will be closed and the magnet will again act upon the wheel Y to give it fresh impulse. The position of the scroll X, projection Z, and strip N, at the time when Z strikes the upper end of N, is indicated in dotted lines.

From the foregoing it will be obvious that after the pendulum or other oscillating device has been manually set in motion, such device or the part projecting therefrom will strike the support of the contact mass C, thereby separating that contact from the opposed abutment F; immediately that the oscillating device swings in the opposite direction, the mass C flies back and strikes its opposed abutment, and by reason of the resiliency of one or both of them the mass C rebounds, and continues such action repeatedly but at regularly decreasing intervals, until it is hit another blow by the oscillating device or else comes to rest against the opposed abutment and closes the circuit through the battery and magnet M, thus permitting the full current to flow through the magnet and cause it to exert magnetic force 60 to pull the pendulum bob toward it, as the

air space between them decreases when the bob swings toward the magnet poles, thereby giving the pendulum a fresh impulse and increasing the arc of its swing.

As heretofore stated, the magnet M is constructed so as to have considerable self-induction in its circuit, and therefore during the time that the contacts C and F are rapidly striking together and separating by reason of their resiliency, the current which passes through the circuit W, W, and magnet M, during the instants of contact of C with F, is so small as to be negligible and the magnet is not sufficiently energized to produce any appreciable effect upon the pendulum. So long as the amplitude of the arc of the pendulum swing is sufficient to enable it to return and strike the contact C before it has ceased to vibrate by reason of its resiliency, such contact will be given an additional impulse, but each succeeding one not quite so powerful as the previous one, and thus the recurring oscillations of the pendulum and the periods of vibrations of the mass C will gradually diminish until the latter will come to rest in contact with the abutment F during the interval occupied by the pendulum in swinging away from and back to the support of the mass C. During this period of rest or continued contact between C and F, the full current will pass through the magnet M, and by thus energizing it give another impulse to the pendulum, which will cause it to strike the support of the contact C with greater force, and the same cycle of operations will be repeated. These two contacts C, F, operating in this manner act as a "time limit" relay, which operatively closes the circuit only after varying limits of time determined in this case by the extent of the arc through which the oscillating device moves.

Under some conditions it may be found desirable to duplicate the make-and-break mechanism C, F; locating devices similar to those shown in Fig. 2, for instance, upon the opposite side of the pendulum rod, as illustrated in Fig. 4, where the two sets of devices are shown as practically independent. Added reliability is thus secured because either battery will continue to drive the pendulum if the other fails. By omitting battery I' and wire W² and connecting the two magnets M by wire W³, the apparatus may be operated by a single battery; and instead of duplicating the magnet M, as shown, it may be located beneath the bob B in a vertical line passing through the support U, and the magnetic material on the lower end of the bob omitted at the middle portion and applied only at the outer portions, or the middle portion of the bob may be cut away. Any other electrical means than an electromagnet may be used in the circuit with contacts C, F, to add energy to the oscillating device, with the same result. Under some

conditions it may also be found advantageous to interpose an ordinary electric relay in the circuit between the contacts C, F, and the device employed to add energy to the oscillating device; under which conditions it would require no greater current through those contacts than would be necessary to operate such relay. When thus arranged the main electric circuit would be made and 10 broken at the relay contacts.

I claim:—

1. The combination of an oscillating device, electrical means to give it added impulse when oscillating, an electric circuit including such impulse means and also resilient make-and-break devices, one of which latter devices is adapted to be set in vibration in relation to the other, by the impact of the oscillating device, and thus interrupt 15 the electric circuit for periods of time which vary in proportion to the variation in the length of the arc through which said oscillating device swings.

2. The combination of an oscillating device, electrical means for imparting added energy thereto when oscillating, a movable mass capable of sustained vibration against an abutment, an abutment with which such mass makes impact and against which it is 25 normally at rest, means for periodically communicating motion of the oscillating device to said mass, to separate it momentarily from its abutment, and a source of electric energy in circuit with the means for imparting energy to the oscillating device and with 30 electric conducting contacts on the said mass and its abutment.

3. The combination of an oscillating device, electrical means to give it added impulse when in oscillation, an easily movable mass which has an electric contact and is resiliently supported near the end of the arc in which the oscillating device swings, an abutment of electric conducting material against 40 which said mass may strike and rebound, means to cause the oscillating device to throw the mass from its abutment at the end of each oscillation, and an electric circuit including said impulse adding means, the said 45 mass and its abutment.

4. In mechanism for propelling clocks and similar apparatus at uniform rate of speed, an electric circuit, a time-limit relay therein consisting of a mass, resiliently supported so 55 as to be adapted to vibrate for limited varying periods, an abutment against which said mass strikes during vibration; means for starting the mass into vibration and electrical contacts upon the mass and its abutment through which the circuit is closed 60 when the mass is at rest against the abutment.

5. A time-limit relay for an electric circuit, consisting of a mass of material resiliently supported so as to be adapted to vi-

brate for limited intervals of time against an abutment, an abutment against which said mass will strike and rebound during vibration, means to start the mass into vibration, and electric contacts upon the mass and 70 its abutment through which the circuit is closed when the mass ceases vibration and is at rest against the abutment, and by which an added impulse of vibration is caused to be imparted to the said mass. 75

6. The combination of a freely oscillating device, a pair of readily separable electrical contacts which will vibrate by resilient force when given sudden impact together, means operated by the oscillating device to throw 80 one of said contacts from the other, an electrical device which has self-induction in its circuit and which gives added impulse to the oscillating device whenever the extent of its swing is below normal, and an electric circuit which includes the impulse device and 85 said separable contacts.

7. In electrical apparatus for propelling clock and similar mechanism at uniform rate of speed, a freely swinging pendulum, 90 electrical means to give added impulse thereto when its swing is below normal, an electric circuit including such means, and a make-and-break device consisting of contacts, one or more of which are of resilient material, 95 and which normally tend to remain together, means operated by the pendulum to separate said contacts at one limit of its vibration and a device upon the pendulum to act directly upon the mechanism to be propelled. 100

8. The combination of an oscillating device, an electric circuit, readily separable contacts and electrical means to impart energy to the oscillating device, in said circuit, means operated by the oscillating device to 105 set said contacts into vibratory impact, and auxiliary contacts in the circuit which are normally open and are closed by the oscillating device at the outer portions only of its are of vibration. 110

9. The combination of an oscillating device, an electric circuit, electrical means in the circuit to impart energy to the oscillating device, primary electric contacts which are separated by the oscillating device, but 115 which normally close the circuit, and secondary contacts normally open, but which are closed by the oscillating device during a portion only of its arc of vibration.

10. The combination of an oscillating device, an electric circuit, electrical means actuated by the oscillating device to maintain its oscillation, and auxiliary means in the electric circuit which automatically prevent the flow of current therein when the 120 oscillating device is at rest. 125
